UNITED STATES PATENT OFFICE.

FRANK L. IRWIN AND JOHN E. TESSEYMAN, OF COLUMBUS, OHIO, ASSIGNEES TO THE
RALSTON STEEL CAR COMPANY, OF COLUMBUS, OHIO, A CORPORATION OF OHIO.

HOPPER-CAR.

1,062,237.

Specification of Letters Patent. Patented May 20, 1913.

Application filed May 26, 1911. Serial No. 629,712.

To all whom it may concern:

Be it known that we, FRANK L. IRWIN and JOHN E. TESSEYMAN, citizens of the United States, residing at Columbus, in the county 5 of Franklin and State of Ohio, have invented certain new and useful Improvements in Hopper-Cars, of which the following is a specification.

Our invention relates to improvements in 10 hopper cars especially of the twin type, and has particular reference to the construction of a cross hood and the means for reinforcing the same and of securing it at its ends to the center girder and sides of the car.

15 In the drawings which are hereto attached and hereby made a part of this specification, Figure 1 is a vertical longitudinal section through one end of the car taken on a line between the center sill and side of the car, 20 showing our improvements; Fig. 2 is a vertical transverse section through the car near one end between the end-slope sheets and cross hood along the line A—A of Fig. 1; Fig. 3 is a side view of the reinforcing dia- 25 phragm or cross bearer indicated at 38 in Fig. 1 showing the connection thereof with the center sill and the side of the car, the cross hood being omitted in this view and other features. Fig. 4 is a top plan view of 30 the cross hood illustrating especially the connection thereof with the center sill. Fig. 5 is an enlarged detail of the cross hood in vertical transverse section, between the center sill and side of the car with the reinforcing diaphragm shown in place, said figure showing essentially the cross hood features 35 of Fig. 1 only on a larger scale.

In the drawings, 1 is the center sill construction, formed, in this instance, of parallel channels having their flanges inwardly disposed; 2 indicates the end slope sheets, 3 is the side of the car, 4 is the center sill hood extending longitudinally of the car, and secured at end 5 to the end slope sheets, 45 in a well known manner, and at the cross hood it is secured in a manner hereinafter described. An outside side stake of the car is shown at 6, and the angle 7 is connected thereto through the side of the car near the bottom thereof at 8, and at the top of the car is likewise provided an angle 9 which is secured at 10 through the side 3 of the car and flange 11 of the outside side stake 6; likewise, secured to the side 3 of the car and

outside stake 6, is the inside side stake 55 formed of the member 12 having the flange 13 thereon through which rivets 14 secure the same to the side of the car, and having the wide flange 15 thereon extending inwardly, and hereinafter more fully de- 60 scribed; the second member 16 and the member 12 are connected as shown at 17, the member 16 being riveted to the side of the car at 18 through its flange 19.

Extending from the sides of the car to the 65 center sill is a hood formed of a single sheet of metal, folded as shown at 20, to form the vertical sides having an interval between the same, and having the downwardly diverging sides 21 and 22; or if preferred, two sheets 70 of metal may be employed, shaped so as to form the hood as here shown, meeting along their upper edges, where, as above described, the fold is formed in the single sheet. Upon the lower edge of each of these diverging 75 sides is secured an angle 23, riveted thereto as shown at 24, the said angle extending from the outer edge of the sheet 21 to the center sill 1. The angle 25 is applied to the center sill and the cross hood sheet 21 to 80 unite these members, and is riveted to both as shown at 26 and 27. To connect the cross hood and center sill hood, we provide the tie or saddle member 28, which overlies the ridge 20 and the inner ends of the cross hood 85 sheets and is secured thereto as shown at 31; said member 28 is formed with the flange portions 29 thereon overlying the center sill hood and secured thereto as at 30.

At their outer ends, the cross hood sheets 90 are secured to the sides of the car, and at their inner ends are secured to the center sill, as described; further, they are connected to the lower ends of the inside side stakes as appears at 36, said stakes being bent outwardly at their lower ends to take over the ridge of the cross hood, whereby the cross hood is strongly reinforced against stresses operating both transversely and longitudinally of the car. The rivets 37 extend 95 through the inside side stakes, the folded or vertically flanged portion of the cross hood sheet, and the diaphragm reinforcing member now to be described.

Referring especially to Fig. 3, a cross 105 bearer or diaphragm reinforcing member 38 is provided, flanged at its inner end and lower edge, and is secured at 39 through its

inner end flange 40 to the vertical web of the center sill; and through its lower edge flange 41, said diaphragm 38 is secured by the rivets 42 to the compression member 43, which is arranged transversely of the center sill and secured thereto at 44. Said diaphragm member 38 is secured at its outer end to the side 3 of the car by means of an angle member 45 which is applied to the diaphragm member and the side of the car and secured thereto at 46 and 47, the rivets 47 passing through the said angle 45 and the side of the car and the flange 48 on the outside side stake. The angle 45 at its lower end is bent to overlie flange 50 of angle 49 secured at 51 upon the lower edge of the side 3 of the car. A tension member 52, which in the present instance is an angle, is applied transversely to the upper flanges 53 and 54 of the center sill, and securely riveted thereto at 55 and 56; at 57 said tension member is secured to the cross bearer or diaphragm reinforcing member 38, and on the opposite side of the center sill the tension member is similarly secured as at 58, to the opposite diaphragm member. The compression member 43 is secured to the lower flange of a similar diaphragm reinforcing member which is not herein shown, on the opposite side of the center sill, being similar to the diaphragm member 38 in all respects.

Referring especially to Fig. 5, it is seen that the upper edge of the diaphragm member 38 lies within the fold 20 of the upper portion of the cross hood sheet, and is secured to the vertical sides thereof by means of rivets shown at 59. In this manner the cross hood is supported from beneath, and, as described above, is united to the center sill and the side of the car and to the compression and tension members described, whereby the construction of the car at this point is strongly reinforced; the reinforcing diaphragms on opposite sides of the center sill are securely tied together as stated above; further, the cross hood is greatly reinforced at its junction with the center sill hood by means of the saddle or tie member 28, and the stresses set up in this region of the car by its operation are efficiently absorbed.

Many advantages accrue in operation from our combination of the style of cross hood herein described with the reinforcing diaphragm, and we do not desire to confine ourselves to the specific construction shown, but desire to have the advantage of all variations and changes which lie within the scope of the appended claims.

What we claim is:

1. In a hopper car having a center sill, a cross hood formed of a sheet folded along its upper edge, secured to the center sill and to the sides of the car, a cross bearer

secured to the center sill and to the side of the car and having its upper end positioned within the fold of said sheet and being secured thereto, and a member mounted transversely upon said center sill and being secured thereto and to said cross bearer. 70

2. In a hopper car having a center sill and sides, a cross hood formed of a sheet of metal bent to form a substantially vertical fold in the upper portion thereof, a cross bearer or reinforcing member positioned within said fold and secured thereto, and means for connecting said cross bearer at its ends to said center sill and a side of the car. 75

3. In a hopper car having a center sill and sides, a cross hood construction at each side of said center sill formed of a sheet of metal bent to form a substantially vertical fold in the upper portion thereof, a cross bearer or reinforcing member positioned within said fold in each of said cross hood constructions, and secured thereto along its upper edge, and means for connecting said cross bearer at its ends to said center sill and a side of the car and a member overlying said center sill and secured thereto and to said cross bearer, in each of said cross hoods. 80 25 90

4. In a hopper car having a center sill and sides, a cross hood construction at each side of said center sill formed of a sheet of metal bent to form a substantially vertical fold in the upper portion thereof, a cross bearer or reinforcing member positioned within said fold in each of said cross hood constructions, and secured thereto along its upper edge, and means for connecting said cross bearer at its ends to said center sill and a side of the car and a member overlying said center sill and secured thereto and to said cross bearer, in each of said cross hoods, and a connecting member uniting the inner ends of said cross hood constructions and continuing said cross hood over said center sill. 100 105 110

5. In a hopper car having a center sill and sides, a cross hood construction at each side of said center sill formed of a sheet of metal bent to form a substantially vertical fold in the upper portion thereof, a cross bearer or reinforcing member positioned within said fold in each of said cross hood constructions, and secured thereto along its upper edge, and means for connecting said cross bearer at its ends to said center sill and a side of the car, and a connecting member uniting the inner ends of said cross hood constructions and continuing said cross hood over said center sill. 115 120 125

6. In a hopper car having a center sill, a cross hood formed of oppositely inclined sheets secured at their ends to the center sill and the side of the car, and center sill hood and a connecting member over-lying the 130

inner ends of said cross sheets and said center sill hood and secured thereto.

7. In a hopper car having a center sill and center sill hood, a cross hood formed of 5 oppositely inclined sheets secured at their ends to the center sill and the sides of the car, means united to the side of the car for reinforcing said cross hood, and a connecting member over-lying the center sill and

being secured to the cross hood sheets and to 10 the center sill hood.

In testimony whereof we affix our signatures in the presence of two witnesses.

FRANK L. IRWIN.

JOHN E. TESSEYMAN.
